UNITED STATES PATENT OFFICE.

CHARLES S. BARON, OF TIFFIN, OHIO.

LIQUID CONTAINER WITH DETACHABLE TOP.

Application filed March 11, 1921. Serial No. 451,648.

To all whom it may concern:

Be it known that I, CHARLES S. BARON, a citizen of the United States of America, and resident of Tiffin, in the county of Seneca, 5 in the State of Ohio, have invented certain new and useful Improvements in Liquid Containers with Detachable Tops, of which the following is a specification, reference being had to the accompanying drawing.

- 10 My present invention comprehends pitchers, jugs and containers generally for liquids. Specifically it relates to molasses jugs, and has for its object the production of a container preferably made of glass, in 15 which provision is made preferably in the shape of the container itself and in mechanism carried by the top therefor, for detachably fastening the top to the container by means which are not only positive and 20 efficient for holding the top in place when applied to the container, but whose movable retaining members are also located inside the container, and concealed and protected thereby.
- 25 A container and top of the type just referred to, not only present an outward appearance that is pleasing and slighty, but afford means for promoting the sanitary cleanliness of the utensil in respect to the 30 facility with which the top and the container may be separated and cleaned. The means employed for uniting the top and container by my present invention have, in addition to other advantages of utensils 35 of its class, the particular advantage of affording a certain and practically complete security of union between the top and the container.

What constitutes my invention will be 40 hereinafter specified in detail and succinctly set forth in the appended claims.

In the accompanying drawing,

Figure I is an inside view of the top 45 of a container, equipped with my invention, the body of the container being illustrated in cross section.

Figure II is a vertical section on the line II-II of Figure I.

Figure III is a vertical section on the 50 line III-III of Figure I.

Figure IV is a view similar to Figure III showing a slight modification in respect to the clip members of the top which serve to fasten it to the body of the container.

55 Referring to the numerals on the draw-

ing, 1 indicates the body of a container that may be of any usual or preferred shape and dimensions and made of any suitable material, that at present generally in use being glass. The body 1 may be as usual, provided upon opposite sides, respectively, with a handle 2 and a spout 3.

The upper edge that defines the mouth of the container body 1 is, in accordance with my present invention, preferably made flush, so as to accommodate upon it a flat-lying top, that is made of two parts 4 and 5. The part 4 is designed to be fixed but detachably fastened to the body 1, while the part 5 is united to the part 4 as by a usual hinge connection 6. The part 5 is preferably provided with a thumb piece 7 for tilting the part 5 to open position against the closing resistance of a coiled spring 8.

The elements above enumerated and so far as described above are such as are well known in the art, and may be all of any usual or preferred material form, construction, and relationship.

My present invention resides in means that are to some degree specific for securing the part 4 of the top, and incidentally the part 5 thereof, to the body 1.

To that end I provide upon the side 85 of the body 1 that is adjacent to the handle 2, a stop piece, preferably a skirt 10, that depends from the part 4 of the top, and, engaging the body 1, confines the part 4 thereon against any tendency towards transverse movement in the direction of the spout 3.

Cooperative with the skirt 10, for the purpose of fastening the part 4 of the top to the body 1, I provide upon the part 95 4 within the said body one or more and preferably two resilient yielding members 11 and 12.

The members 11 and 12, preferably consist of a pair of strong spring clips constituting resiliently spreading members terminally disposed upon the respective ends of a resilient bar 15 and substantially at right angles thereto, that is secured medially, as by rivets 16, to the underside of the part 4 105 of the top. The members 11 and 12 are formed to present their entire outer or engaging surfaces in close contact with the internal surface of the container with whose contour they conform, thus insuring a maxi- 110

mum area of frictional contact therewith. Both of the said members 11 and 12 are preferably contrived to constitute, in respect of the top, forward propelling members. That is to say, they functionate to effect a tendency to drive the top 4—5 transversely across the mouth of the container body 1 in the direction of the spout 3. This propelling tendency is resisted by the presence of a stop 10 piece, for example the skirt 10, upon the part 4 with the effect of contributing additional security of union between the top and the container. The propelling action just referred to is secured by locating the bar 15 in chordal disposition upon the part 4 to the rear of the transverse diameter of the top so as to present the resilient members 11 and 12 at an angle to the respective portions of the inside periphery of the container 20 which they engage.

The feature of angularly disposed members 11 and 12, as has just been specified, is preferential only, and may be omitted if desired, within the broader purview of my invention.

Always, the essential function of the members 11 and 12 is to effect a practicably secure union between the top and the container by means of resiliently acting members each 30 extending longitudinally within said container and having its disposition substantially parallel to the longitudinal axis of the container. This construction is distinguished from devices in which the top is 35 secured by spring wing attachments secured to the underside of the top, and working parallel to the plane of the top. As contra-distinguished therefrom, my members 11 and 12, working as specified, parallel to the longitudinal axis of the container, effect a frictional engagement with the sides of the container of enlarged area, as compared with former devices, which, in many cases, will be found sufficient in itself 40 to hold the top and container together. To illustrate, in Figure IV, for example, I show a straight container neck 18 and simple straight terminal clips, which correspond respectively to the members 11 and 12 45 aforesaid, but which, for the purpose of distinction, are numbered 19 and 20, respectively. The only difference between the clips 19 and 20 and the members 11 and 12 respectively, is that said clips are entirely 50 straight and depend only upon friction to hold them in place within the neck 18. They may be also disposed with added security of union at an angle to the inside periphery of the neck, operating against a skirt 10 with holding effect, in the manner 55 already described.

In the form of embodiment of my invention preferred, however, I use the members 11 and 12 complete, each being provided with a preferably terminal catch 21

which is adapted positively to engage a shoulder 22 that is formed on the inside of the container body, and extending outside the periphery of the mouth is accommodated, in shape and in operative disposition, 70 to the catch 21. When the members 11 and 12 are provided each with the catch 21 for cooperation with the shoulder 22, each of the members 11 and 12 with its respective catch 21, becomes a latch that is made effective by the resiliency, upon opposite sides of the medially located rivets 16, of the bar 15. Consequently, there is secured not only an expansive resiliency of the members 11 and 12, but a pulling resiliency that acts in 75 lines parallel to the longitudinal axis of the container. The effect is positively to draw the top towards the container, and snugly to hold it in place upon the same against intrusion of dust or insects, which is the object to guard against in all devices in the class to which my invention belongs.

The shoulder 22 is shown in Figure II as a sharply defined bevel, and that is its preferred form; but a rounded effect as 80 shown in Figure III of the shoulder 22 may be employed. In fact, the precise shape of this shoulder, even if employed, is not a material feature except in so far as it is necessary to capacitate it positively to engage the catches 21.

In operation, the top, in any form in which my invention may be embodied, is applied by inserting the members 11 and 12, or their equivalents, into the neck of the 100 container, and gently forcing the top into place against the mouth of the container, where the resiliency of the members 11 and 12 will suffice to hold it against such separating strain as may be developed in ordinary 105 use. To remove the top, as it becomes necessary to do in order to wash the parts, it is sufficient to pull upon the thumb piece 7 with sufficient force to overcome the yielding resistance of the members 11 and 12 or 110 their equivalents, whether they be augmented by the catches 21 or not. In this connection, it may be observed that in tilting the part 5 of the top, which is done in pouring out the contents of the container 1, pressure is applied downwardly upon the thumb piece. It is necessary to pull upon the thumb piece in the opposite direction, only when it is desired to separate the top 115 from the container.

What I claim is:

1. The combination with a container body having an open mouth substantially circular in cross section, of a top consisting of two parts hinged together, a stop piece on one of said parts adapted to engage the outside wall of the container, a resilient bar secured to the part last named in chordal disposition to the mouth of the container and in the rear of the transverse diameter.

- thereof, and members angularly disposed towards the periphery of the container on the opposite extremities of the said bar extending with spreading resiliency longitudinally into and in contact throughout their lengths with the inner wall of the container so as to operate with propulsive force against the container and the resistance of the stop piece to secure the top to the container.
2. The combination with a container having an open mouth, a substantially cylindrical neck defining said mouth, and an outwardly flaring body, of a top consisting of two parts hinged together, one of said parts being provided with a pair of resilient spreading members angularly disposed toward the periphery of the container and extending longitudinally in the direction of the axis of the container and in contact with the inner wall of the neck thereof, a terminal catch on each of said spreading members conformable to and contacting with the shoulder formed at the juncture of the neck and flared body of the container, and a stop piece for engaging the outer wall of the container, the said stop piece being secured to the same part of the top that carries the spreading members and coacting with said members to secure the top to the container.
3. An open mouthed container body provided below its mouth-defining wall with an internal shoulder outwardly flared from said wall and adapted for operative engage-
- ment with a latch upon a detachable top for securing said top to the container.
4. The combination with a container body having an open mouth and provided with an internal shoulder, of a top consisting of two parts hinged together, one of said parts being provided on the outside of the container with a stop piece adapted to engage the container, and being provided within the container with a spring finger extending longitudinally into the container in contact with the inner wall thereof, the resiliency of said finger serving to urge said stop into engagement with the container and thereby to secure the top thereon, said spring finger having a catch adapted to engage said shoulder.
5. The combination with a container body having an open mouth and provided with an internal shoulder, of a top consisting of two parts hinged together, one of said parts being provided with a pair of oppositely spreading spring fingers extending longitudinally into the container in contact with the inner wall thereof, at least one of said fingers being provided with a catch adapted to engage said shoulder.

In testimony whereof, I have hereunto set my hand in the presence of two subscribing witnesses.

CHARLES S. BARON.
